[57] CLAIM

The ornamental design for an umbrella stand, as shown and described.

DESCRIPTION

FIG. 1 is a front elevational view of umbrella stand showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is an exploded perspective view in folded condition; and,

FIG. 9 is a perspective view in position of use, the broken lines indicate environmental structure and form no part of the claimed design.
